CLAIM

The ornamental design for a vertical panel, as shown and described.

DESCRIPTION

FIG. 1 is a perspective view of a vertical panel according to a first embodiment of our new design;

FIG. 2 is a front plan view thereof;

FIG. 3 is a back plan view thereof;

FIG. 4 is a left side view thereof;

FIG. 5 is a right side view thereof;

FIG. 6 is a top plan view thereof;

FIG. 7 is a bottom plan view thereof;

FIG. 8 is a front plan view of a second embodiment of the vertical panel, having the same appearance as FIGS. 1 through 7;

FIG. 9 is a front plan view of a third embodiment of the vertical panel, having the same appearance as FIGS. 1 through 7; and,

FIG. 10 is a front plan view of a fourth embodiment of the vertical panel, having the same appearance as FIGS. 1 through 7.

The longer dash-dash broken lines illustrate environmental structure and form no part of the claimed design.

The shorter dash-dash broken lines, in FIGS. 1, 2, 6, 8, 9 and 10, is meant to portray an unclaimed structure (e.g. an electronic display panel) that can illuminate from inside the vertical panel and be perceived therethrough.
